(57) **CLAIM**

The ornamental design for a two-compartment food package, as shown and described.

DESCRIPTION

FIG. 1 is a front perspective view of a container showing my new design, from above and one side;

FIG. 2 is a front elevational view thereof;

FIG. 3 is a back elevational view thereof;

FIG. 4 is a side elevational view thereof;

FIG. 5 is a side elevational view of the other side thereof;

FIG. 6 is a top plan view thereof; and,

FIG. 7 is a bottom plan view thereof.

This design shows a two-compartment food package suitable to package for example a soup or a sauce product. The package is divided in two parts, which are separated by a separating seal having the shape of a wave.
